FIBRE CONTAINER

Robert D. Minteer, Webster Groves, and Lester B. Leighton, Clayton, Mo., assignors to The Greif Bros. Coop-
erage Corporation, Delaware, Ohio, a corporation of
Ohio

Application March 14, 1952, Serial No. 276,552

1 Claim. (Cl. 229—4.5)

This invention relates to an improved fibre drum or container.

Fibre drums and containers are characterized by a tubular body portion made of convolutely wound layers of kraft or similar fibre board. Drums and containers of this type are frequently used for bulk shipments of chemicals, raw materials, or the like. As originally shipped from the manufacturer, a certain type of labelling is required or desired on the outer surface of the container. In the course of merchandising the materials, it is frequently necessary or desirable to change the labelling. This procedure has required the use of extraneous labelling which impairs the appearance of the container or has required reprinting, repainting, or otherwise mutilating the surface of the container.

It is an object of the present invention to overcome these difficulties and disadvantages and to provide an improved fibre drum or container having a removable sheath encasing the body portion and presenting the same appearance as the surface of the container to which the original marking or labelling may be applied. Thereafter, during the course of merchandising or using the product, the sheath may be readily removed when relabelling is required, or desired, without impairing the appearance of the container so as to expose the surface of the body of the container.

A further object is the provision of a fibre drum or container having an improved removable sheath of the above character which is secured in position and assembled with the drum in an improved fashion so as to simplify the manufacture of the drum and so that it can be readily removed without defacing the drum or impairing the function thereof.

Other objects will appear from the following detailed description of the drawings in which:

Fig. 1 is a perspective view of a drum embodying our invention in its original condition with the sheath applied thereto;

Fig. 2 is a side elevational view of the drum, with the locking rim removed, showing the sheath in the process of being removed from the drum;

Fig. 3 is a side elevational view of the assembled drum after the sheath has been fully removed;

Fig. 4 is a detailed sectional view of the upper portion of the drum after the sheath has been removed;

Fig. 5 is an elevational view partially in longitudinal section showing the assembled drum in its original condition with the sheath applied thereto;

Fig. 6 is an enlarged sectional view, with the central portion omitted, of one side wall of the drum in its original condition with the sheath applied thereto; and

Fig. 7 is a cross-sectional view in the direction of the arrows on the line 7—7 of Fig. 5.

Our invention is applicable to fibre drums or containers. The expression fibre drums or containers is used in the trade to designate containers having a tubular body made from laminated layers of convolutely wound fibre material such as kraft board. The body por-

2

tion of the drums are generally formed by winding kraft or fibre board, to which an adhesive or resin has been applied, around a mandrel until a drum body of the required strength and thickness has been formed.

5 In the accompanying drawings we have illustrated our invention as applied to one type of fibre drum or container having a tubular body portion 10 with a bottom closure 11 permanently secured to the lower end thereof, and having a rigid binding 12 secured over the open upper end thereof. A removable head 13 is provided for the open upper end and a split clamping ring 14 serves to embrace the upper end of the container and releasably hold the head in place.

The body of the container is tubular in form and has a side wall 15 formed of laminated convolutely wound layers of kraft or fibre board.

The bottom closure 11 consists of a metal disc 16 which may have a non-metallic seal or gasket 17 on the inner surface thereof. The metal disc and non-metallic gasket extend downwardly as shown in Fig. 6 over the lower end of the container wall and then are extended outwardly into beaded interengagement with the body wall. The interengagement may be accomplished in the manner taught in patent application Serial No. 99,476 of Herbert L. Carpenter filed June 16, 1949, for Fibre Drums Having Metal Closures and Method of Making the Same, by flaring the lower end of the body wall outwardly before the adhesive has set and while the laminated wall is still workable and thereafter applying the metal disc and gasket and rolling them inwardly with the flared end of the laminated body wall into a tight beaded interengagement. It will be understood, of course, that any other type of bottom closure may be used with the drum.

35 Near its upper end the body wall 15 is deformed or beaded inwardly as shown at 19 so as to provide an internal rib and an external groove in registry with each other spaced a short distance beneath the upper end of the container. The binding or reinforcing rim 12 preferably takes the form of a metal sheet or strip tightly embracing the outer surface of the upper end of the body wall and fitted tightly into the groove as shown. It is also extended over the top surface of the body portion and crimped inwardly as shown at 20 in Fig. 6 so that the crimping 20 and the interengagement with the groove serves to hold the binding or rim in place.

The removable head or closure 13 may be of any desired type embracing, resting on, or fitting into the upper end of the container. In the illustrated embodiment the head takes the form of a wooden portion 13 fitted into the upper end of the container and resting on the internal rib and a supplementary head or gasket 21 made of strong paper, fibre board, plastic or metal extending over the inner surface of the wooden head thence upwardly over the top surface of the body wall and downwardly for a short distance over the outer surface of the side wall as shown most clearly in Figs. 4 and 5.

The split clamping ring 14 is in the form of a split metal band of a size to embrace the end of the container body with its two ends in overlapping relationship. Locking rims of this type are shown in prior Patent No. 2,382,858 of Herbert L. Carpenter granted on August 14, 1945, and are provided with an apron portion 22 which engages in the external groove and with an in-turned flange 23 which overlaps the head or closure 13. The interengagement between the clamping ring and the external groove together with the overlapping of the head serves to hold the closure in place. The clamping ring may be expanded to release it or contracted to lock it by means of lever 24 which extends between the two overlapping ends of the locking ring 14 and is pivotally

connected at 25 and 26 respectively to the two ends of the ring. When the lever is in horizontal position the ring is contracted and when the lever is elevated the ring is expanded. The pivotal pin 25 is positioned past center with respect to the pivotal pin 26 so as normally to retain the ring in contracted or locked position. A small strap 27 may be struck outwardly from the surface of the ring to interengage with the hooked end portion of the lever 24 when it is in locked position. When the lever is in horizontal position and in engagement with the strap 27 the ring is contracted and will serve to retain the cover in place.

The drum as heretofore described is one type of drum to which our invention is applicable but it will be understood that our invention may be applied to other types of convolutedly wound fibre drums and containers.

Our invention resides primarily in the provision of a sheath 30 embracing the body wall and preferably taking the form of a layer of fibrous material similar to the kraft or fibre board from which the body wall is made. The sheath is preferably free from any direct attachment by adhesives, nails, staples, rivets, or the like with the side wall. It is held in place by being tightly extended around the body wall with the two edges in overlapping relationship as shown at 31. The sheath is applied to the body wall before the binding or protecting rim 12 is secured in place and extends from approximately the upper portion of the external groove downwardly to a point immediately adjacent the bead 18. When the binding or protecting rim 12 is applied to the upper end of the container and secured in place it embraces the end of the sheath as shown at 32 thereby frictionally holding the sheath in place.

When the drum is completed the sheath 30 presents the same appearance as the outer surface of the container body and the casual observer would not realize that the drum was provided as an extraneous sheath. Suitable labelling or printed matter may be applied both to the surface of the drum body 15 and to the surface of the sheath 30. The labelling material and information contained on the sheath 30 may be applicable to the initial shipment and merchandising of the contents of the container, whereas the labelling appearing on the surface of the body 15 may be applicable to subsequent merchandising operations or to the use of the product. When the labelling appearing on the outer sheath has served its purpose the sheath may be slit longitudinally from the lower edge of binding 12 to the bottom of the sheath and thereafter pulled outwardly so that it tears along the lower edge of the binding 12. In this fashion the edge of rim 12 serves as a cutting edge in the nature of a straight edge or paper knife along which the sheath is severed. Under certain circumstances the sheath may fit loosely enough beneath the binding 12 so that it may be completely removed from beneath the binding. However, in other cases the binding frictionally grips the sheath and the sheath is severed along the binding, leav-

ing the upper edge of the sheath beneath the binding as shown at 32 in Fig. 4.

In those cases where the locking ring 14 extends downwardly beneath the lower end of binding 12 it may be desirable to remove the locking ring 14 before severing the sheath. Thus, in Fig. 2 the drum is illustrated with the locking ring removed and with the sheath in the process of being severed along the lower edge of binding 12. After the sheath is removed the drum continues to present the same complete appearance as it originally presented with a different surface exposed on which new and additional labelling is or can be displayed.

It will thus be seen that we have provided an improved drum or container having a tubular body made of laminated convolutedly wound layers of fibrous material having an encasing sheath presenting substantially the same appearance as the surface of the tubular body and which can be readily removed to expose the body surface. It will also be seen that suitable indicia, markings or labelling material may be applied both to the body surface and to the sheath so that one set of markings is originally displayed and when desired can be readily replaced by the other set of markings. Modifications may of course be made in the illustrated and described embodiment of our invention without departing from our invention as set forth in the accompanying claims.

We claim:

30 An improved fibre drum comprising: a tubular body portion made of convolutedly wound laminated layers of fibrous material; a bottom closure secured to the lower end of the body portion; a metal binding strip tightly embracing the outer surface of the upper end of said body portion; and a sheath made of a layer of fibrous material substantially similar to the material of the body portion tightly surrounding the body portion with its longitudinal edges secured to each other in overlapping relationship and with its upper edge positioned between the binding and the body portion so as to be frictionally held in position with the remainder of the sheath being free from attachment to the body portion, said sheath extending from the binding strip to a point adjacent the bottom closure so as to present the same external appearance as the body portion of the drum and said metal binding presenting a relatively straight cutting edge along the lower surface thereof whereby the sheath may be readily severed along the binding to be removed from the drum.
